(57) **CLAIM**

We claim the ornamental design for a rail bracket, as shown and described.

DESCRIPTION

FIG. 1 is a perspective view of a rail bracket showing our new design;

FIG. 2 is a side view thereof;

FIG. 3 is an opposite side view thereof;

FIG. 4 is a front view thereof;

FIG. 5 is a rear view thereof;

FIG. 6 is a bottom view thereof;

FIG. 7 is a top view thereof; and,

FIG. 8 is a perspective view of the rail bracket shown holding a rail.

The broken lines shown in the drawings depict an environment of use that forms no part of the claimed design.
